(57) **CLAIM**

The ornamental design for a display screen with graphical user interface, as shown and described.

DESCRIPTION

The FIGURE is a front view of a display screen with graphical user interface showing the claimed design. The exterior uneven-length broken lines illustrate a display screen and form no part of the claimed design. The remaining even-length broken lines illustrate portions of the graphical user interface and form no part of the claimed design. The diagonal-lined hatch depicts a contrast in appearance.
